DESIGN FOR A STOOL

Florence M. Wray, West Nyack, N. Y.

Application January 4, 1939, Serial No. 82,137

Term of patent 14 years

To all whom it may concern:

Be it known that I, Florence M. Wray, a citizen of the United States, residing in West Nyack, county of Rockland, and State of New York, have invented a new, original, and ornamental Design for Stools, of which the following is a specification, reference being had to the accompanying drawing, forming part thereof.

The figure of the drawing is a perspective view of the stool, embodying the invention.

I claim:

The ornamental design for a stool, substantially as shown.

FLORENCE M. WRAY.
